(57) **CLAIM**

We claim the ornamental design for a coaxial connector, as shown and described.

DESCRIPTION

This application is related to concurrently filed, co-pending, and commonly assigned U.S. Patent application Ser. No. 09/826,292 entitled "Cable Network Interface Circuit," the disclosure of which is hereby incorporated herein by reference.

FIG. 1 is an isometric view showing the inner end of our design for a coaxial connector. The dotted material is to show the environment and is not part of the design;

FIG. 2 is an elevation view of the inner end of our design for a coaxial connector showing a bent center connector;

FIG. 3 is an elevation view of the outer end of our design for a coaxial connector;

FIG. 4 is a side elevation view of our design for a coaxial connector, the other side being a mirror image;

FIG. 5 is a top elevation view of our design for a coaxial connector;

FIG. 6 is a bottom elevation view of our design for a coaxial connector;

FIG. 7 is an isometric view showing an alternative embodiment of the inner end of our design for a coaxial connector showing a straight terminal;

FIG. 8 is a side elevation view of FIG. 7 of our coaxial connector; and,

FIG. 9 is a bottom elevation view of FIG. 7 of our coaxial connector.
